UNITED STATES PATENT OFFICE.

MERRILL B. KNIGHT, OF OZONE PARK, NEW YORK, ASSIGNOR TO THE ROBERT GRIFFIN COMPANY, A CORPORATION OF NEW YORK.

DESIGN FOR WALL PAPER.

Application filed March 14, 1922. Serial No. 1,161. Term of patent 3½ years.

To all whom it may concern:

Be it known that I, MERRILL B. KNIGHT, a citizen of the United States, and a resident of Ozone Park, in the county of Queens and State of New York, have invented a new, original, and ornamental Design for Wall Paper, of which the following is a specification, reference being had to the accompanying drawings forming part thereof.

In the drawings the figure shows a portion, which is to be repeated in the production of wall paper, of the wall-paper design embodying my invention.

I claim:

The ornamental design for wall-paper as shown.

MERRILL B. KNIGHT.
